United States Patent Office

Des. 183,039

Patented June 17, 1958

183,039

BIDET

Henry Dreyfuss, New York, N. Y., assignor to Crane Co.,
Chicago, Ill., a corporation of Illinois

Application June 5, 1957, Serial No. 46,500

Term of patent 14 years

(Cl. D4—5)

Fig. 1.

Fig. 2.

Fig. 3.

Fig. 1 is a front perspective view of a bidet embodying my new design.

Fig. 2 is a side view thereof.

Fig. 3 is a top plan view.

The opposite side of the bidet is substantially the same in appearance as the side disclosed. The dominant features of the bidet are shown in solid lines.

I claim:

The ornamental design for a bidet, substantially as shown and described.
